SAIL BATTEN

Charles R. Newpher, Shaker Heights, Ohio, assignor to
The Glastic Corporation, Cleveland, Ohio, a corporation of Ohio

Filed June 28, 1965, Ser. No. 85,937

Term of patent 14 years

(Cl. D71—1)

FIG. 1

I claim:

The ornamental design for a sail batten, substantially as shown and described.
